[57] CLAIM

The ornamental design for a pet watering vessel, as shown and described.

DESCRIPTION

FIG. 1 is a front elevational view of a pet watering vessel embodying my new design;

FIG. 2 is a side elevational view thereof, the side opposite appearing substantially the same as the side shown;

FIG. 3 is a rear elevational view thereof;

FIG. 4 is a top plan view thereof; and

FIG. 5 is a bottom plan view thereof.

Fig. 1.

Fig. 2.

Fig. 3.

Fig. 4.

Fig. 5.
